WHEELED SKATE

Arthur G. Bentley, 18655 Clark St.,
Tarzana, Calif. 91356

Filed Oct. 26, 1971, Ser. No. 192,699

Term of patent 14 years

Int. Cl. D21—01

U.S. Cl. D34—14 C

FIG. 1.

FIG. 2.

FIG. 3.

FIG. 4.

FIG. 5.

FIG. 6.

FIG. 1 is a perspective view taken from the right front of a wheeled skate showing my new design;

FIG. 2 is a top plan view of the same;

FIG. 3 is a left side elevational view thereof as seen in FIG. 1;

FIG. 4 is a rear elevational view;

FIG. 5 is a bottom plan view; and

FIG. 6 is a perspective view, similar to FIG. 1, of a modified form of my new design wherein the wheel arrangements have been reversed.

I claim:

The ornamental design for a wheeled skate, as shown and described.
